(57) **CLAIM**

The ornamental design for a cue rack, as shown and described.

DESCRIPTION

FIG. 1 is a right-front perspective view of a cue rack that incorporates my new design.

FIG. 2 is a left-front perspective view thereof.

FIG. 3 is a front view thereof.

FIG. 4 is a right-side view thereof.

FIG. 5 is a left-side view thereof.

FIG. 6 is a back view thereof.

FIG. 7 is a top view thereof; and,

FIG. 8 is a bottom view thereof.

The broken line showing of the feet, handle, hardware elements, depressions, cut-outs, and accessories are for illustrative purposes only and form no part of the claimed design.
